UNITED STATES PATENT OFFICE.

JOKUM J. MUNSON, OF MILWAUKEE, WISCONSIN.

TENT.

Application filed February 20, 1922. Serial No. 538,022.

To all whom it may concern:

Be it known that I, JOKUM J. MUNSON, a citizen of the United States, and resident of Milwaukee, in the county of Milwaukee and

5 State of Wisconsin, have invented new and useful Improvements in Tents, of which the following is a description, reference being had to the accompanying drawings, which are a part of this specification.

10 This invention relates to improvements in tents, and more particularly to the closure means provided for the opening to the tent.

The primary object of the invention is the provision of a pair of curtains arranged to close the opening to the tent, the adjacent or meeting edges of said curtains being supported by elastic members, for example, of rubber tubing, the upper and lower ends of which are fixed to suitable supports, where- 20 by said edges are normally held taut in closed position to exclude insects and the like, but may be readily forced apart suf- ficiently to permit a person to pass through therebetween.

25 In its preferred form the invention contemplates providing two spaced supporting posts to which the sides of the tent are fastened and a horizontal member attached to the upper ends of said supporting posts; and a more specific object of the invention 30 is the provision of a pair of curtains to close the space between said supporting posts, which curtains are fixed at their upper edges to the horizontal member and at their outer

35 edges to the respective posts, the adjacent edges of the curtains preferably overlapping each other and being supported by elastic members attached at their upper ends to the horizontal member and at their lower ends 40 to a second horizontal member, for example, a rope drawn taut and the ends of which are attached to the respective supporting posts adjacent the ground.

The invention consists in the novel constructions and arrangements to be herein- 45 after described and claimed for carrying out the above stated objects and such other ob- jects as will appear from the following de- 50 scription of a certain preferred embodiment illustrated in the accompanying drawings, wherein—

Fig. 1 is a perspective view of a tent embodying the principles of the invention; and

55 Figs. 2 and 3 are sectional views, on an

enlarged scale, taken on the lines 2—2 and 3—3, respectively, of Fig. 1.

Like characters of reference designate like parts in the several views.

Referring now to the accompanying drawings, it will be seen that the invention is illustrated as embodied in a tent 5 of rectangular shape and having an extension portion 6. The extension portion includes a pair of vertical corner supporting posts 7 spaced the desired distance apart and attached at their upper ends to a horizontal member 8, the entrance to the extension portion and the tent proper being through the space defined by said posts 7 and the member 8. The sides of the extension portion are covered by strips 9 of canvas, the front edges of which are fixed to the respective posts 7 and the rear edges of which are attached to the front edges of the respective side walls 10 of the tent proper. The preferred manner of joining the adjacent edges of the walls 9 and 10 is shown in detail in Fig. 3, the wall 10 carrying a reinforcing strip 10^a and the wall 9 being slipped into place between the strip 10^a and the adjacent side of the main wall 10. The strip 9 may be secured in place by sewing it to the wall 10 and strip 10^a or by employing rivets or the like. The top of the extension portion 75 is, of course, covered by a strip of canvas, not appearing in Fig. 1, and not shown in detail, as it forms no part of the present invention.

The opening to the extension portion of 90 the tent is closed by two curtains 11 and 12, which may be of mosquito netting, or any other desirable material, having their upper edges attached to the horizontal member 8 and their outer edges attached to the re- 95 spective posts 7. The curtains are prefer- ably made wide enough so that their adja- cent edges overlap each other substantially as shown in Figs. 1 and 2. A horizontally 100 extending member 13, which may be in the form of a rope, or the like, extends from one post 7 to the other, being drawn quite taut and attached thereto adjacent the ground. In order to hold the overlapping portions of the two curtains in close engage- 105 ment so that insects or the like cannot enter the tent therebetween, the inner edges of the curtains 11 and 12 are attached to elastic members 14, which may be in the form of rubber tubing, these members being attached 110

at their upper ends to the horizontal member 8 and at their lower ends to the member 13. It will now be apparent that the meeting edges of the two curtains will be held 5 taut at all times, but may readily be separated sufficiently to permit a person to step through therebetween to enter or leave the tent.

While two curtains are preferably employed for closing the space between the posts 7 and the member 8 the adjacent edges of which are supported by elastic members in order to provide ample room for a person to pass therebetween, it will be obvious in 10 some constructions that a single curtain might be employed one edge of which would be supported by a member normally closely positioned against a relatively stationary piece of canvas or the like, in that event the 15 last mentioned member would have sufficient elasticity to permit it to be moved aside so that a person might enter or leave the tent.

I claim:

- 25 1. In a tent, the combination of two closure curtains arranged to partially overlap each other, the overlapping edges of said respective curtains being supported by elastic members, and means to which the extremities of said members are attached, for the purpose specified.
- 30 2. In a tent, the combination of a pair of spaced vertical supports, a horizontal member connected to the top of said supports, a pair of curtains fastened at the top to said member and at their outer sides to said respective supports, the adjacent edges of said respective curtains being supported by elastic members, said elastic members at their upper ends being fixed to said horizontal member, and means to secure the lower ends of said elastic members.

3. In a tent, the combination of a pair of spaced vertical supports, a horizontal member connected to the top of said supports, a pair of curtains fastened at the top to said member and at their outer sides to said respective supports, the adjacent edges of said respective curtains being arranged to partially overlap each other and being supported by elastic members, said elastic members at their upper ends being fixed to said horizontal member, and means to secure the lower ends of said elastic members.

4. In a tent, the combination of a pair of spaced vertical supports, a horizontal member 55 connected to the top of said supports, a pair of curtains fastened at the top to said member and at their outer sides to said respective supports, the adjacent edges of said respective curtains being supported by elastic members, said elastic members at their upper ends being fixed to said horizontal member, and a second horizontal member positioned adjacent the ground and extending 60 from one of said supports to the other, the lower ends of said elastic member being fixed to said second horizontal member, for the purpose specified.

5. In a tent, the combination of a pair of spaced vertical supports, a horizontal member connected to the top of said supports, a curtain having its upper edge and one side edge fastened, respectively to said member and one of said supports, an elastic member attached to the other free edge of said curtain, said elastic member having its upper end fixed to said horizontal member, and means to secure the lower end of said elastic member.

In testimony whereof, I affix my signature.

JOKUM J. MUNSON.
